[57] CLAIM

The ornamental design for a pulling and lifting winch, as shown and described.

DESCRIPTION

FIG. 1 is a left side elevational view of a pulling and lifting winch showing my new design;

FIG. 2 is a top plan view thereof;

FIG. 3 is a right side elevational view thereof;

FIG. 4 is a front elevational view thereof;

FIG. 5 is a rear elevational view thereof;

FIG. 6 is a left side elevational view of a second embodiment of the pulling and lifting winch;

FIG. 7 is a top plan view of FIG. 6;

FIG. 8 is a right side elevational view of FIG. 6;

FIG. 9 is a front elevational view of FIG. 6;

FIG. 10 is a rear elevational view of FIG. 6;

FIG. 11 is a perspective view of the embodiment of the invention shown in FIG. 1; and,

FIG. 12 is a perspective view of the embodiment of the invention shown in FIG. 6.

FIG. 6

FIG. 7

FIG. 8

FIG. 9

FIG. 10

FIG. 12

FIG. 11
